Fig. 5.

Fig. 6.

Fig. 7.

Fig. 8.

Fig. 9.

Fig. 10.

Fig. 11.

Fig. 12.

FIG. 1 is a top plan view of a battery terminal cleaner and shaper embodying the first embodiment of my new design;

FIG. 2 is a side elevational view thereof;

FIG. 3 is a bottom plan view thereof;

FIG. 4 is a side elevational view thereof;

FIG. 5 is a left end view thereof;

FIG. 6 is a right end view thereof;

FIG. 7 is a top plan view of a battery terminal cleaner and shaper embodying a second embodiment of my new design, said second embodiment being substantially the same as the first with added end collars and removable fasteners;

FIG. 8 is a side elevational view thereof;

FIG. 9 is a bottom plan view thereof;
 FIG. 10 is a side elevational view thereof;
 FIG. 11 is a left end view thereof;

FIG. 12 is a right end view thereof.

I claim:

The ornamental design for a battery terminal cleaner and shaper, as shown and described.
